(No Model.)

C. E. WEBER.

WINDOW SHUTTER.

No. 271,384.

Patented Jan. 30, 1883.

UNITED STATES PATENT OFFICE.

CHARLES E. WEBER, OF MONROEVILLE, INDIANA.

WINDOW-SHUTTER.

SPECIFICATION forming part of Letters Patent No. 271,384, dated January 30, 1883.

Application filed September 16, 1882. (No model.)

To all whom it may concern:

Be it known that I, CHARLES E. WEBER, a citizen of the United States, residing at Monroeville, in the county of Allen and State of Indiana, have invented a new and useful Window-Shutter, of which the following is a specification, reference being had to the accompanying drawings.

This invention relates to window-shutters, and has for its object to provide certain new and useful means for adjusting the slats thereof so that the vision may be unobstructed, to admit of the slats being opened any desired space and securely fastened from outside interference, and to provide, also, a simple, durable, inexpensive, and efficient device.

In the drawings, Figure 1 is a perspective view of a panel of my improved shutter. Fig. 2 is a vertical sectional view thereof. Fig. 3 is a horizontal sectional view on the line *x x*, Fig. 2. Fig. 4 is a perspective detail view of one of the slat-staples. Fig. 5 is another vertical sectional view on line *y y*, Fig. 3; and Fig. 6 is a detail sectional view.

Referring to the drawings, A designates the frame, in which are pivoted the cross-slats B. One of the sides C of the frame is provided on its inner edge with a vertical groove, D, into which opens a slot, E, in the face of side C, on the inside and at the lower end. The groove D forms a vertical slot, F, at the top and bottom, where the cross-pieces G G of the frame join the side piece, C.

H is a vertically-sliding bar or rod, which works in groove D, and is retained in place by slots F F. It is provided with a screw pin or bolt, I, projecting through slot E, and provided with a thumb-nut, J. The surface of side piece, C, around slot E is preferably faced with a metallic plate, K, against which nut J binds. Bar H is provided on its inner edge with a row of staples, L, through which pass staples M,

depending from the edge of slats B. Staples M are substantially U-shaped, and have their ends N N bent inwardly. The ends N N are driven into the edge of the slat, and the U-body M extends down from the edge, as shown, below the pivot of the slat.

The operation and advantages of my invention will be readily understood. When nut J is loosened it may be used as a knob to elevate or lower rod H, the screw-bolt I moving in slot E. This movement of rod H will of course act, through staples L M, to open or close the slats to the desired point, when by tightening nut J the slats and rod H will be locked in position.

The device is exceedingly simple and convenient, and may be manufactured at about the same cost as the former style with a central rod. Besides, it is far more durable in construction.

I claim as new—

1. The combination of the frame having the pivoted slats B, provided with edge staples, M, and piece C, having longitudinal edge groove, D, terminating in a slot at each end, and slot E, a sliding operating-bar, H, having a row of edge staples, L, and a screw pin or bolt, I, and a thumb-nut, as set forth.

2. The combination, with the slats B, adapted to be operated by a sliding bar at the edge, and pivoted in the frame, of the substantially U-shaped staples M, having inturned ends aud arranged to depend from the end of the slat, as set forth.

In testimony that I claim the foregoing as my own I have hereto affixed my signature in presence of two witnesses.

CHARLES EDWARD WEBER.

Witnesses:

JNO. A. CORBALEY,
FRANKLIN FREESE.
